UNITED STATES PATENT OFFICE.

HARRY WARD LEONARD, OF BRONXVILLE, NEW YORK.

ELECTRIC CONTROLLING DEVICE.

No. 902,307.

Specification of Letters Patent.

Patented Oct. 27, 1908.

Application filed May 13, 1905. Serial No. 260,198.

To all whom it may concern:

Be it known that I, HARRY WARD LEONARD, citizen of the United States, residing at Bronxville, in the county of Westchester and State of New York, have invented certain new and useful Improvements in Electric Controlling Devices, of which the following is a full, clear, and exact specification.

My invention relates to devices for controlling electric motors and other translating devices, and especially to rheostatic controlling means provided with automatic protective devices.

The object of my invention is to improve the efficiency, reliability and construction of such controlling devices, and to accomplish these results, I embody in combination various important features among which the following may here be referred to. I provide means for automatically protecting the motor armature, or other translating device, upon the occurrence of "no-voltage" or "low voltage." In my preferred form the no-voltage device is an electro-magnetic device responsive solely to the voltage to which the motor armature may be subjected, and which is independent of the current in the motor armature or field winding. I also provide means for automatically protecting the motor armature against abnormally large currents. In my preferred form this overload protective device is in the form of an electro-magnetic circuit breaker, so functionally related to the circuit to be protected, that the circuit breaker is always in a protective condition, regardless of the condition or position of other devices affecting the device to be protected. I also provide rheostatic means for controlling the flow of current in the circuit. In my preferred form, the resistance controlling arm or device, is so functionally related to the overload device, that a protective amount of resistance must be in the path of the circuit to be established before the circuit can be closed by closing the overload device or otherwise. In my preferred form, the circuit can be opened by the resistance controlling arm. In order to reduce the arc, which is formed when the circuit is opened either by the resistance controlling arm or by the circuit breaker, to a minimum amount and thus practically eliminate its destructive effect, I provide efficient arc-rupturing means. This is preferably an auxiliary, automatically, quick acting switch by which the circuit is

finally broken and which acts quickly independently of the slowness of movement of the part breaking the circuit, such as the resistance controlling arm. I also preferably provide a magnetic blow-out which produces a strong magnetic field at the point, or points, where the circuit is finally broken and so reduce the arc formed to its minimum amount. I may provide either the resistance controlling means, or the overload device, or both, with such protective means, and in my preferred form both such parts are thus protected. I also provide means which automatically acts to quickly and efficiently close the circuit, independently of the slowness of movement of the operator's hand, when he performs the acts necessary to close the circuit. This will prevent the operator from making an improper or insufficient contact in closing the circuit. The circuit connections of the armature and field of the motor are such as to always keep the armature and field windings in a closed circuit so as to avoid any detrimental effect due to the inductive discharge of the field. The no-voltage magnet is connected so that it is never subjected to any abnormally high electromotive force, such as might be due to field discharge.

In certain cases, I provide means for obtaining control of the speed of a motor by both armature and field controlling means which are so arranged that the motor cannot be started with an improperly weak field. I preferably arrange the controlling means in such a manner that the field is automatically maintained at full strength so long as there is rheostatic resistance in series with the armature, and so that the field can be weakened at the will of the operator to obtain the highest speeds after the armature resistance has been cut out. This may be accomplished by a single operating lever, or other moving device.

My invention will be understood by reference to the accompanying drawings taken in connection with the following description.

Figure 1 is a plan view of a panel or support showing the controlling and protective devices thereon; Fig. 2 is a similar view of a portion of Fig. 1 with some parts shown in another position; Fig. 3 is a section on the line 3—3 of Fig. 1 with the overload arm removed; Fig. 4 is a face view of one of the blow-out magnets; Fig. 5 is a sectional view thereof; Fig. 6 is a bottom view of the end

of the resistance controlling arm; Fig. 7 is an end view thereof with some parts broken away showing one of the shoes in section; Fig. 8 is a side and end view of part of the 5 quick make device; Fig. 9 is a diagram of connections of the parts shown in Fig. 1; Fig. 10 is a plan view of a modified form of controlling and protective device; Fig. 11 is a detail of interlocking means; Figs. 12 10 and 12^a are detail views of one form of switch contacts; Fig. 13 is a diagram of connections of Fig. 10; Fig. 14 is a face view of a modified form of controlling device adapted also to vary the field strength; Fig. 15 15 is a diagram of connections thereof; Fig. 16 is a face view of a modification and Fig. 17 is a diagram of connections thereof; Fig. 18 is a face view of a controlling device in which the resistance arm controls the main 20 switch; Fig. 19 is a face view of another form having additional protective devices; Fig. 20 is a face view and also showing connections of a modified form having means for reversing the motor; Fig. 21 is a face 25 view and also showing connections of another form of reversing means; Fig. 22 is a detail of the reversing switch; Fig. 23 is a face view of a modification in which the field is controlled and interlocked reversing 30 means is provided; Fig. 24 is a detail view; Fig. 25 is a diagram of connections of the construction shown in Fig. 23; Fig. 26 is a face view also showing connections of a modification having an interlocked reversing 35 field rheostat; Fig. 27 is a similar view with a modified form of interlocking means; Figs. 28 and 29 are detail views of a modified form of contact devices; Fig. 30 is a face view also showing connections of a modified 40 form of controlling means adapted for units of large capacity; and Fig. 31 is a detail view.

Referring to Fig. 1 the controlling and protective devices are shown mounted upon 45 a panel 1 of insulating material, such as slate, and are thus all united into one complete unit. At the top of the panel are indicated the terminals for the motor and the supply wire connections. Protective 50 fuses of the inclosed type are indicated at 2. The supply wires are connected directly to these fuses, which act after a certain time interval and thus protect the motor and all parts on the panel from overload currents 55 and serve as a protective means in addition to the electromagnetic circuit breaker in case the latter should fail to act. A main switch 3 is connected in the main circuit for opening both poles of the supply circuit. The rheostat contacts of the motor starter 60 shown in this figure are indicated at 4, and preferably mount the starting resistance in the back of the panel.

The movable starting arm is shown at 5, 65 is outer end moving over the contacts 4

In order to insure contact over a large area, I provide the movable arm with a yieldable contact preferably divided into a plurality of parts, and each part is independently spring pressed. The construction of one 70 form is shown in Figs. 6 and 7. The contacting parts are shown as a plurality of skate shoes 6, rectangular in outline and comparatively long and narrow, with curved ends and extending lengthwise across the 75 arm; that is, the shoes extend lengthwise in the direction of movement. Each shoe is pressed against the resistance contacts by a spring 7 at each end. Each spring is partly 80 inclosed in a tubular case 8, which has a closed rounded outer end, and which end seats in a considerably larger depression in the shoe. The spring and its case extends into a considerably larger hole drilled in the lower face of the arm, there being one hole 85 for each spring. A flexible conductor 9 is secured to each shoe and also to the arm 5, giving direct electrical connection between the parts. The above construction secures 90 excellent contact between the shoes and resistance contacts, gives uniform pressure and will permit the parts to be readily renewed or replaced. Also by reason of this construction, the contact skate can be raised off 95 from the contact segments at either end to a great amount, while preserving perfect and ample contact at the other end of the skate so that this very flexible form of skate contact rides very readily over any obstruction 100 in its path, such as a burned surface, due to arcing, without breaking the circuit or seriously affecting the contact. This is quite important, not only as regards maintaining good contact, but also as otherwise the retractile spring of the controller arm might 105 fail to turn the arm to the initial position on account of friction or obstructions, due to imperfections in the surface of the contacts. I prefer to use copper for the contact skates, and brass for the stationary contact segments which tends to reduce abrasion of the contact surfaces. The narrow long skate 110 form of contact is very advantageous because it permits of obtaining, upon a modern length of stationary contact segments, a 115 number of independent, self alining, flexible contacts which are readily removable and renewable.

The arm 5 is arranged to open the circuit when in the off position on the insulating strip or blind contact 10. In order to obtain the quick break of the circuit in the presence of a strong magnetic field, I mount upon the panel adjacent to the initial resistance contact an ironclad magnet 11, shown more in detail in Figs. 4 and 5. This consists of a central core and an outer shell surrounding the same and joined to or integral with the core at the rear end thereof. A magnetizing coil 12 surrounds the core and is connected in 120 125 130 135 140 145 150 155 160 165 170 175 180

circuit as hereinafter explained. Fixed to the face of the magnet and extending between the central core and a projecting portion of the top part of the shell, is a non-magnetic contact piece 13, preferably of copper. This is thus located in the path of an intense magnetic field from the end of the core to the top portion of the shell and any rupture of circuit taking place at the face of 5 the contact piece will be in the presence of a strong magnetic field, giving an efficient magnetic blow out. The contact piece 13 may have an extension 14 for connection of the circuit thereto, which may also be used 10 in some cases for maintaining connection with the auxiliary contact.

The controlling arm carries the auxiliary contact piece 15 which is movably mounted upon the arm and electrically connected thereto by a flexible connection. This contact piece in the present instance, is T or Y shaped in its general outline, the side extensions being curved and fitting loosely under the heads 16 of the pins or screws fixed 20 to the arm 5. A wire 17 may be passed through the two heads 16 which will prevent them from turning and working loose and may also serve, in some constructions, to retain the contact piece or "flipper" 15 in 25 place. A spring 18 is inserted between the central portion of the auxiliary contact and an abutment on the arm so as to constantly force the contact outwardly and cause the two extensions to seat under the heads 16. If the controlling arm is moved to off position, the auxiliary contact will engage the contact 13 before contact is broken at the initial resistance contact. As the movement is continued, the contact of the shoes 6 will be 30 broken with the initial resistance contact, and the piece 15 will be deflected by engaging the side of contact 13. Upon further movement, the piece 15 will move over the face of the contact 13 and when the contact 35 is finally broken, the auxiliary contact 15 will be rapidly thrown away from 13 by the spring 18 which always tends to return the auxiliary contact from a deflected position. The final rupture of the circuit will therefore 40 take place in a strong magnetic field and with a very quick action. Furthermore the parts which are subjected to wear or deterioration are readily replaceable in a simple manner.

55. In order to avoid the objectionable effects of a slow or insufficient closing of the circuit, I provide means for a quick make. A post or support is mounted on the base and carries a pivoted member 19 adjacent to the 50 contact 13. The member 19 is pressed by a spring, as shown in Fig. 8, so that the outer end is held in the path of a projection or pin 20 on the auxiliary contact 15. The under surface of the member 19 is preferably inclined as shown. Starting from the off po-

sition, as the arm is moved forward, the contact 15 will engage and pass around the end of the member 19 and be deflected. When the disengagement takes place, the piece 15 will be thrown rapidly and firmly 70 against the contact 13 or its extension and close the circuit with an efficient contact. The main connection between the arm and initial resistance contact will now be made before engagement of the auxiliary contacts 75 is broken. The top of the projection 20 and the under face of the member 19 are beveled in such a direction, as shown in Figs. 7 and 8, that upon the return of the controlling arm, the beveled under face of the member 80 19 will engage the beveled top surface of the projection 20. This will cause the member 19 to be raised against the pressure of its spring out of the path of the projection 20; consequently on the return movement, 85 the member 20 does not check the movement of the auxiliary contact or interfere with the quick break movement thereof. The controlling arm 5 is thus provided with a quick make and quick break which acts very 90 rapidly without reference to the slow movement of the arm.

In the final position the no-voltage, or low voltage magnet 21, will retain the arm in 95 place by attracting the armature 22 pivoted to the arm. In the final position the auxiliary contact 15 will engage the post 23 and cause the field connections, as well as those of the magnet 21 to be connected across the supply line independently of the armature 100 resistance as will afterward be explained.

In addition to the controlling arm 5, I have provided an arm 24 pivoted on the same pivot with arm 5 and coupled thereto by a spiral spring within the hub 25 on 105 arm 24, which spring tends to force the two arms together. The arm 24 carries the main current from one supply line and acts as the overload circuit breaker in conjunction with the overload coil 26. When the circuit is 110 closed, the latch 27 retains the arm in position against the spring pressure, and upon overload, the plunger of coil 26 rises and trips the latch to release the arm 24. The latch is pivoted on a pin or post 28 and actuated by a spring 29 encircling the post so as to cause the latch to engage the pin 30 on the underside of arm 24. The arm 24 carries a switch blade 31. From an extension of the frame of the magnet coil 26, project 115 two posts 32. Each post carries two springs 33, and between the two springs on each post are held the two plates 34 having flaring edges to receive the blade 31. By this construction, I secure excellent contact between the parts, and even if they are somewhat out of alinement, the springs will permit compensating movement of the parts and the direct spring pressure of the plates against the switch blade brings the parts 120 125 130

firmly together. From each plate 34, a flexible connection 35 secures electrical connection to the overload coil 26. An extension of arm 24 carries an auxiliary contact 15 similar to that carried by arm 5 and which acts in conjunction with a blow-out magnet 11 in a manner similar to that above described. In this case, the auxiliary quick break with magnetic blow-out will act to break the circuit; that is, when the arm is released, due to the overload current, contact between the main contacts is first broken. The auxiliary contact 15 is deflected in the meanwhile and after the main contact is broken, the auxiliary contact will be broken with a quick action in the presence of a strong magnetic field. Fig. 2 shows the position of the parts when thus breaking the circuit, and Fig. 1 shows the parts in their normal running position.

It will be noted that when the circuit breaker is closed as shown in Fig. 1, the auxiliary contact 15 maintains connection with the auxiliary fixed contact. This is particularly desirable in those constructions in which the movement of the parts is only slight before the main contacts are disengaged, for if the contact 15 passed by the co-operating fixed contact, and out of engagement therewith, then the contact 15 must again engage the co-operating contact within a slight movement of the parts and before the main contacts are disengaged. It is therefore preferable to extend the fixed auxiliary contact as shown so that this connection is not broken when the circuit breaker is closed. This fixed auxiliary contact is provided with a curved or depressed portion as shown so that the end of the "flipper" will engage the same, and when the switch is moved to open the circuit, this curved or depressed portion will catch the end of the "flipper" and deflect the same in the opposite direction, so that the quick break action will take place.

After the circuit is opened by the overload device, the overload switch is closed only by movement of the controlling arm 5. This is accomplished by means of arm 5 or a projection thereof engaging the arm 24 and forcing it to the closed position. This necessitates the returning of the starting arm to its initial open circuit position and in starting again, the circuit will be closed by the starting arm in the manner above described. The starting arm will therefore always be in a protective position when the circuit is closed.

Fig. 9 shows the electrical connections of the form of controlling device shown in Figs. 1 to 8. The supply line is connected to the fuses 2 and current passes from them to the main switch 3. One line from switch 3 passes to the overload coil 26 and thence through the main contacts to arm 24 when

the latter is in operative position. Current also passes in another path to this arm from the same line, through the coil of the blow-out magnet 11 and auxiliary contacts. The arm 5 is in electrical connection with arm 24. The other line from switch 3 passes to the armature A of the motor, and thence to the final resistance contact, then through the resistances to the coil of the magnetic blow-out 11. Thus when the arm is moved to start the motor after the overload switch is closed, the circuit will first be closed across the line by the quick make of the auxiliary contacts on arm 5 and continued movement of the arm will cut out the armature resistance and bring the motor up to speed. The field winding F of the motor is shown as a shunt winding and is connected from one side of the supply line to the blow-out coil 11 of the arm 5, or to the initial resistance contact. The circuit through the field from the supply line is therefore closed when the armature is connected to the supply line, and when the supply current is cut off, the armature and field are closed on themselves through a starting resistance. This provides a path for the field discharge upon opening the supply circuit. The no-voltage magnet 21 is connected from one side of the supply line through a resistance 36 to the blow-out magnet 11, or initial resistance contact. When the circuit is closed by arm 5, the no-voltage magnet will therefore be connected across the line in a circuit independent of the armature or field winding and will therefore act independently of such windings and can not be subjected to any dangerously high electro-motive force due to field discharge voltage. With these connections, when the starting arm is in its final position, the current to the field and no-voltage windings would be obliged to pass through the starting resistance, and in some cases I find it desirable to omit the starting resistance from these circuits and obtain a more direct connection across the line. I accomplish this by connecting one terminal of the field and no-voltage circuits to the post or fixed contact 23. This is placed near the final position of the starting arm, and when the latter is in the final position, the post 23 is engaged by the auxiliary contact 15, as shown in Figs. 1 and 2. This will then give a direct connection from the arm 5 to the field and no-voltage circuits.

In Fig. 9, I have shown means whereby the motor may be stopped from any convenient distant point, which may often-times be desirable. This is accomplished in this instance by interrupting or shunting the current through the no-voltage magnet which will release the arm 5 and cause the main circuit to be opened. A push button is indicated at 37 at one distant point for 120 125 130

breaking the no-voltage circuit and at 38 another push button is indicated at some other desired point. The latter is arranged to close a shunt around the no-voltage magnet which would cause the same to be de-energized and accomplish the same purpose as the interruption of the circuit by means of the push button 37. Any number of push buttons may be employed as the convenience 10 of the operator requires.

Fig. 10 shows a construction which permits the use of a large number of resistance steps and one which is also adapted to carry heavy currents when the two sets of resistances are connected in parallel. Two sets of resistance contacts are indicated at 4, 4', and the opposite ends of the controlling arm 39, carry the contact shoes 6 which pass over the two sets of resistance contacts. The 15 auxiliary quick make and quick break means, together with magnetic blow-out, is applied to the lower end of arm 39. In the form of construction shown in this figure, the arm 39 is not provided with a handle for moving the same, but is controllable by a second arm 40. The two arms are pivoted on the same stud and are interlocked with each other so that there is a certain amount of play between them. The interlocking parts 20 are shown enlarged in Fig. 11. The arm 40 is provided with projections 41 which extend downward into the larger angular openings 42 in the arm 39, giving a certain angular play of arm 40 with reference to 25 the arm 39 without moving the latter. Consequently in starting, the arm 40 will be moved past arm 39 before the latter is moved, and when held by the no-voltage magnet 21 in the final position, the arm 30 40 will be in a position beyond arm 39. The arm 40 is connected with the overload circuit breaker arm 24 by a spiral spring located in the hub 25 formed on the arm 24, which spring tends to force the circuit 35 breaker arm and arm 40 toward each other. Considerable spring tension is therefore exerted on arm 40 when in its final position and when released by the no-voltage magnet it starts into motion with the minimum 40 friction and later will strike against the arm 39 with a hammer blow by reason of the play of the parts and return the resistance arm to off position. This hammer blow action is particularly desirable for large 45 units and where considerable force is needed to start the resistance arm.

When the overload circuit breaker is open, it is closed by manipulation of the arm 40 which engages the overload arm to force it 50 into closed circuit position. In thus closing the circuit breaker, the resistance arm 39 is necessarily moved to the off position by the movement of arm 40 and a protective resistance is therefore always placed in circuit 55 before the motor can be started.

The overload arm carries an auxiliary contact as above explained for securing a quick break and the coöperating auxiliary fixed contact and means for obtaining a strong magnetic field at the point of rupture of the circuit is also shown.

The action of the overload coil 26 to trip the latch 27 is similar to that explained with reference to Fig. 1. The construction of the main contacting parts is however, 70 different. This construction is shown in Figs. 12 and 12^a. The fixed main contact 43 is a laminated one fixed to the panel or support and has the edges of the laminæ turned as shown so as to yield slightly when engaged by the main contact 44 carried by the overload arm 24. The contact 44 is carried by two rods 45 which pass through arm 24 and the flexible connections 46 electrically connect the outer ends of the rods to the 80 arm 24. A spring 47 surrounds each rod and seating against a portion of the arm tends to force the contact 44 outward from the arm and against the fixed contact. The contact 44 is consequently adapted to assume such a position as to accommodate itself to the position of the fixed contact, thereby securing large surface contact and good flexible electrical connection. These contacts may also be readily renewed if necessary.

The electrical connections of the apparatus shown in Fig. 10 is shown in Fig. 13. The connections are similar to some degree to those already described with reference to 100 Fig. 9. It will be noted however, that in the present construction the two initial resistance contacts are connected together, and that the arm 39 will connect the two sets of starting resistances in parallel, the current 105 passing through the overload switch to arm 39 and then divide, passing through the starting resistance in parallel to the motor armature. The connections may be such that the starting resistances will be in series for obtaining a higher resistance with a large number of steps. In such a case the opposite ends of the arm 39 will be insulated from each other and current will pass from, say the lower end of arm 39 through 110 the resistances connected to contacts 4', thence to the upper end of arm 39, through the resistances connected to contacts 4, and then to the motor armature. The contacts 4, 4' will preferably be staggered with reference to each other so that only one resistance step will be cut out at a time.

Fig. 14 illustrates one form of my invention in which the controlling device is adapted not only for starting the motor but for 125 regulating the field strength and armature resistance for the purpose of varying the speed. Fig. 15 shows the electrical connections. A set of armature resistance contacts is shown at 4 and the arm 5' makes electrical 130

connection therewith from the overload arm 24 as in the construction previously described. The arm 5' is not spring pressed and is adapted to remain in any position placed. 5 When in off position the circuit will be opened and the quick make and quick break devices and magnetic blow out are provided as shown. The arm is also provided with a handle for moving to any position desired, 10 and thus include a varying amount of armature resistance for starting or for varying the speed in some classes of work where variation of speed in that manner is desirable. Means is also provided for varying 15 the field strength by varying resistance of the field winding and the controlling arm 5' is adapted to insert resistance in the field by the continued movement thereof after all armature resistance is cut out. Also the construction is such that the field is maintained 20 at its full strength when any resistance is in the armature circuit. The arm carries contacting parts 47, as indicated in Fig. 15, which are electrically connected but insulated 25 from the arm. They contact with two sets of fixed contacts 48, 49 which are passed over by the arm. The set of contacts 48 comprise an initial contact of considerable length which is connected to the initial resistance contact of the armature resistance 30 contacts 4, and the successive contacts 4 are each connected to successive contacts 48. The contacts 48, which are beyond the position of the arm when the last armature resistance step is cut out, are field resistance 35 contacts. The contacts 49 comprise an initial contact of considerable length extending from the off position to the arm to the position occupied by the arm when the last 40 armature resistance step is cut out, and additional contacts which are field resistance contacts. One terminal of the field winding F is connected to the initial long contact 49.

Mounted on the pivot with arm 5' is the 45 no-voltage arm 50. This is interlocked with the arm 5' to such an extent that when the arm 50 is moved to its final position against the no-voltage magnet the arm 5' will be moved sufficiently to close the circuit at the 50 initial resistance contact, but when released from the no-voltage magnet 21, arm 50 will strike against the arm 5' in whatever position the latter may be and force it to the off position. The construction of the overload 55 device is similar to that described with reference to Fig. 10, except that the extension carrying the auxiliary contact 15 is short and at an angle to the arm 24. This arrangement permits the no-voltage arm and 60 controlling arm 5' to have a large range of movement. The no-voltage and circuit breaker arms are spring pressed towards each other.

In operation, if the circuit breaker opens, 65 it will be closed by the operator by moving

the no-voltage arm to engage the controlling arm 5' which in turn will move the circuit breaker to closed position, or the circuit breaker may be closed by movement of arm 5' directly. In either case the starting or 70 controlling arm must be placed in a protective position before the motor can be again started. When starting, the arm 50 is moved against the no-voltage magnet and by reason of a shoulder on its hub which engages a shoulder on arm 5', will, when nearing the no-voltage magnet, cause the arm 5' to move and establish the circuit by the quick make and by moving the skate shoes on to the initial resistance contact. When the circuit is closed by the arm 5' the field of the motor will receive its full strength, current passing from one line through the overload device and arm 5' to the initial armature resistance contact, thence to the initial contact 80 48, through contacts 47 to the initial contact 49, to the field winding and other side of the line. Current will also pass from the initial contact 49 through a resistance 36 and no-voltage magnet 21 to the other side 90 of the line, this magnet being thus connected in a circuit independent of the motor windings. The arm 5' may now be freely moved by the operator. When the arm 5' is moved to cut out armature resistance, the resistance 95 of the field circuit is unchanged, as current will pass from arm 5' to an armature resistance contact, thence to a corresponding contact under the arm, then through contacts 47 to the field. Hence when any armature 100 resistance is in circuit, the field is at its full strength. After the armature resistance is cut out, further movement of the controlling arm will cause the contacts 47 to pass over the resistance contacts 48, 49 and gradually 105 include resistance in the field circuit to cause the speed of the motor to increase. The resistance contacts 48, 49 are preferably staggered so that one step of resistance will be inserted in the field circuit at a time. The 110 final contact 4 is of considerable length in this case in order to maintain the connection while the field resistance is varied. In Fig. 15, means is shown for conveniently stopping the motor from any desired point, such as 115 by push buttons 37, 38 which will interrupt or shunt the current through the no-voltage magnet.

Fig. 16 shows another form of my invention and Fig. 17 the electrical connections. 120 In this construction the panel carries a circuit breaker which cooperates with the other controlling devices to protect the circuit and motor, but in this case is mounted on the panel independently of the controlling and 125 no-voltage arm. The circuit breaker is double pole, each switch 51 being capable of independent operation. The overload coil 52 is connected in series in the main circuit and upon overload is adapted to raise its plunger 130

and engage the latches 53 to cause the release of the spring pressed switches 51 and open both sides of the circuit. The circuit breaker is provided with auxiliary contacts 54 which may be of the type having quick make and quick break with magnetic blow out. The resistance contacts are arranged in two sets 4, 4' which are passed over by the opposite ends of the arm 5^a. The circuit is closed and opened by the quick action of the auxiliary contact 15 carried on the lower end of arm 5^a and which co-operates with the devices as already described to give the desired action. In the final position, the arm is held by the no-voltage magnet 21. It also engages the two laminated contacts 55 by means of the contact 56 carried by the arm. When engaged by the contact 56, the laminated contacts are adapted to yield and the contact 56 is also preferably spring pressed outwardly, as explained with reference to Fig. 12. This construction not only secures good contact, but the pressure exerted is of advantage in giving the arm a quick start from its position of rest, when released by the no-voltage magnet. The necessity of an auxiliary arm, or other device, to give the arm 5^a a blow to start it may be overcome in some cases by this means.

Referring to Fig. 17, it will be seen that the current from one line, passes through the overload coil 52 and through one switch 51 to the arm 5^a. When the circuit is closed by this arm, the current will pass through the two sets of starting resistances in parallel to the motor armature and thence through the other switch 51 to the other line. When the arm 5^a closes the circuit, current also passes through the field winding and no-voltage magnet in independent paths. When the arm is in final position, all armature resistance will be cut out and owing to the connections of contacts 55, current will pass directly from one switch 51 through contacts 55 and switch 56 to the armature. The path of the current through the arm 5^a and its moving contacting parts is therefore avoided. The arm is provided with a spring 57 tending to return it to the off position. In operating this apparatus, the switches 51 should first be closed and then arm 5^a will be moved from off position to close the circuit. If the arm 5^a is moved to start the motor before both switches 51 are closed, the circuit will not be completed, nor will the arm be held by the no-voltage magnet. The switches 51 should be closed one at a time so in case an overload current should flow under any conditions when the second one is closed, as might be the case if the operator held arm 5^a in running position, then the first switch 51 will be automatically opened to break the circuit.

In some forms of my invention, I provide a rheostat having no open circuit position,

but provide means for opening the circuit at another point, at which the quick make and quick break, together with magnetic blow-out, is preferably used. I also control the opening of the circuit, and in some cases 70 also the closing of the circuit at this other point by means of the rheostat arm in various ways and either mechanically or electrically. Figs. 18 and 19 illustrate forms of such construction.

Fig. 18 shows a resistance controlling switch or arm 5^b adapted to pass over the resistance contacts 4 and thus vary the amount of resistance in the circuit. The circuit is opened and closed however, by the main switch 58 pivoted at 59, and adapted to engage the fixed contact 60. Current passes from one side of the line through the switch 58 to contact 60, and thence through the resistance and motor armature A to the other side of the line. Current also passes from contact 60 through the field winding F. The switch 58 carries the auxiliary contact 15 as above described which co-operates with the auxiliary fixed contact 13 which is connected through the blow-out coil to the main contact 60. The member 19 is also provided to co-operate with the pin 20 to give a quick make. Although in some constructions, the switch 58 may be moved 95 slowly, and satisfactory results will be obtained by reason of the action of the auxiliary contacts, I have shown in the present case means for also giving the switch 58 rapid movement and to impart thereto a 100 hammer blow for throwing it. The arm 5^b which controls the switch 58, carries an extension which engages the projecting parts 61 of a hammer 62 pivoted at 59. At one end of the part 62 is a groove or slot 63, through which projects a pin 64 carried by the switch 58 or an extension thereof. In another part of the hammer 62 is a second groove 65, through which projects a pin 66 fixed to the panel or base. A spring 67 connects the pin 66 to a central point at the opposite end of the hammer.

When the arm 5^b is moved to start the motor, the extension will engage one projection 61 and turn the hammer on its pivot until the axial line of the spring has passed the center of pivot 59, when the spring will then act to throw the hammer quickly to strike the pin 64 and thus close the main switch. The arm may then be moved as desired to vary the resistance. When nearing the off position, the extension of arm 5^b will engage the other projection 61 and turn the hammer so that it will strike the pin 64 to open the switch 58. There is therefore no 12¹³ opening of the circuit at the resistance contacts and the main switch is likewise protected from detrimental arcing. Also the opening and closing movement of the main switch is controlled by the resistance arm 14

and the circuit can only be closed when a protective amount of resistance is in the circuit.

Fig. 19 shows a construction similar to Fig. 18 with overload and no-voltage protective devices. In this construction the resistance controlling arm 5^c is spring pressed to bring the same to the off position and is therefore adapted for use as a starting device. The resistance arm will control the operation of the main switch 58 as described with reference to Fig. 18. Also the no-voltage magnet 21 will hold the arm in final position and protect it from no-voltage or abnormally low voltage. In this construction the overload switch 68 is mounted separately from the controlling arm. The overload switch is spring pressed tending to throw it away from the coöperating contact 68^a, and is retained in closed position by the latch 27, which will be tripped to release the switch upon occurrence of overload. The overload switch 68 is provided with an auxiliary quick break contact 15 which acts as already explained to make the final break of the circuit in the presence of a magnetic field.

The current passes from one supply line through the overload coil 26 which acts to trip the latch 27 upon the occurrence of an abnormally large current, then passes through the overload switch to the main switch 58, through the resistance and motor armature to the other side of the line. The resistance arm is provided with an extension 69 which coöperates with an extension 70 of the overload switch 68 whereby the overload switch is closed by movement of the resistance arm to the off position. By reason of this construction, the overload switch is closed at a time when a protective amount of resistance is in circuit. Also the main switch 58 is closed only at a time when a protective amount of resistance is in circuit.

Fig. 20 shows another form of my invention in which a reversing rheostat is shown. In this construction I prefer to interlock the reversing controller in some manner with no voltage and overload protective devices. The rotation of the motor is reversed by reversing the armature current. The controlling arm passes over armature resistance contacts 4 for rotation in one direction and over contacts 4^a for rotation in the opposite direction. The arm carries two insulated conducting portions 71, 71^a, the former connecting contacts 4 with conducting strip 72, or contacts 4^a with 72^a, and the latter connecting 72^b with either 72^c or 72^d. The controlling arm carries the auxiliary contact 15 which is electrically connected with the conducting portion 71, and when approaching or leaving the contacts 4 coöperates to give the quick make and quick break in the magnetic field. It acts similarly when approach-

ing or leaving the contacts 4^a. The contact 15 is provided with a second pin 20' to coöperate with the member 19' to give the quick make when approaching contacts 4^a. This pin is short and the member 19' is at a correspondingly low level, so that this pin will not engage the member 19 when moved in the opposite direction. Also the pin 20 is situated beyond the member 19' and therefore is not in its path. It will be understood that the top of pins 20, 20' is beveled in opposite directions since the direction of movement is opposite when the circuit is made in each case.

The overload and no-voltage protective means is shown mounted apart from the controlling arm. The overload switch 24' is retained in place by the latch 27 which is tripped by the plunger of overload coil 26. The switch 24' carries the auxiliary contact 15 to coöperate with the auxiliary fixed contact 13 to give the quick break in the magnetic field. The no-voltage arm or switch 73 is pivoted and in electrical connection with the overload switch 24'. A spring 57' tends to press the two parts toward each other. The switch 73 carries an iron part 22 which will be attracted and held by the no-voltage magnet 21. When the switch is closed, it engages the fixed main contact 73'. It is also provided with the auxiliary contact devices for obtaining a quick break in a magnetic field. The overload switch is closed by turning the no-voltage switch in a left-handed direction and by interlocking means, the no-voltage switch cannot be closed until the rheostat controlling arm is in off position. The complete circuit will therefore always be closed by moving the rheostat arm from off position which necessarily includes a protective resistance in the circuit at the time of closing. In order to interlock the protective devices and the controlling arm, I provide a pivoted lever 74, one end of which is normally pressed by gravity or other pressure against the hub of switch 73. This hub is notched at one point to receive the end of lever 74 when the switch is in the open position as shown, and when in this position, the switch cannot be closed until the end of the lever is withdrawn from the notch. This open position of switch 73 will be taken if released from the no-voltage magnet, or in case the overload switch is opened and the switch 73 is operated to close the overload switch. When the resistance controlling arm is in the off position, the end of the arm will engage one end of the lever 74 and cause the opposite end to be withdrawn from the notch of the switch 73. The switch 73 is therefore free to be closed only when the controlling arm is in off position.

The connections will be understood from Fig. 20. Assuming that the starting arm is

in off position, the overload switch will be closed by operating the no-voltage switch and then the no-voltage switch will be closed and held by the magnet 21, which is in an independent circuit across the line. If the controlling arm is now moved to the initial contact 4, current will pass from one side of the line through the no-voltage and overload switches, overload coil 26, through the resistance to conductor 71, 72 through the armature A, to 72^c, 71^a, 72^b, to the other side of the line. The amount of resistance in the armature circuit will be varied by varying the position of the arm. When the controlling arm is moved to engage contacts 4^a, current will pass from one side of the line, through the protective devices, through the resistance to 71, 72^a, through the armature in the opposite direction, to 72^d, 71^a, 72^b, to the other side of the line. As the field connections across the circuit remain unchanged, the rotation of the motor is reversed. Of course, the same number of contacts 4^a may be used for the reverse as for the forward speeds, but a less number is shown, as usually only a low speed in the reverse direction is required.

Fig. 21 indicates a construction whereby a reversal of the motor is obtained, all parts are protected from sparking, and protection to the circuit is always secured. The starting and protective devices are similar to those described in connection with Fig. 1 as indicated. In coöperation therewith is a double throw switch having four switch blades 74 in this instance, which coöperate with four contacts 74^a when thrown in one direction and with four contacts 74^b when thrown in the opposite direction. Of these contacts, one of each set, namely 74^c, is provided with shorter contact clips than the others as shown in Fig. 22, and these shorter clips are connected in the circuit of the no-voltage magnet 21.

In operation, the switch blades 74 will be thrown to engage say the upper set of contacts. The circuit breaker arm will be closed by means of the resistance controlling arm and the circuit will be finally closed by means of the resistance arm. Current will then pass from one side of the line through the left-hand switch blade to the left-hand contact 74^c, through the overload coil 26, overload switch, arm 5, armature resistance, to third switch blade 74 from the left, through the armature A, to fourth switch blade, to the other side of the line. The field F is connected across the line from the initial resistance contact to the other side of the line. The resistance arm will be held in final position by the magnet 21 which is connected across the line in an independent circuit, current passing from the second switch blade, to the short contact 74^c, through magnet 21 and resistance 36 to the other side of

the line. Now if it is desired to reverse the motor, the double throw switch may be raised from contacts 74^a to open the circuits. In doing this, contact with the short clip 74^c will first be broken which will interrupt the no-voltage circuit and release the arm 5. The arm will be quickly thrown to off position and open the circuit. Meanwhile the motor armature and field will form a closed circuit through the starting resistance and any objectionable effect of inductive discharge of the field will be overcome. Consequently when the double throw switch is opened to break the remaining contacts, the only circuit to be broken will be this closed circuit of field and armature and as the current therein will be very slight or practically absent, there will be no sparking at the switch contacts. On throwing the double throw switch to engage the lower contacts, the connections will be similar to those above described except that the current through the armature will be reversed, which will reverse the rotation of the armature. In raising the reversing switch from the lower contacts, the circuit of the no-voltage magnet will first be broken as above explained and no sparking takes place at the main switch contacts. It will be observed by this construction that all burning of the contacts of the knife blade switch 74 will be avoided as this switch is closed only under conditions of open circuit and is opened only while the insignificant field current is flowing through it.

Fig. 23 shows a construction in which means for reversing is provided and for varying the speed by varying the field strength as well as the armature resistance, all by means of a single operating device. The construction of the overload and no-voltage protective devices is similar to that explained with reference to Fig. 20, except that the overload switch carries an additional insulated switch blade 24^a with auxiliary contact protective devices so that when the circuit is opened on account of abnormal current, both supply lines will be disconnected, there being two main breaks and two auxiliary breaks in series. The controlling arm 75 carries insulated conducting portions 75^a, 75^b, and 75^c, (see Fig. 25) which make contact with the armature resistance contacts 76, 76' conducting strips 76^a, 76^b, 76^c, 76^d, field resistance contacts 77, 77' and conducting strips 77^a, 77^b. The controlling arm carries the auxiliary contact 15 which coöperates with the fixed contacts when turned in either direction from the off position. In order to produce the quick make, the top part or a projection 20^a on the flipper 15 will engage the members 19^a, 19^b. Instead of having two pins beveled in opposite directions, as explained with reference to Fig. 20, the top part or projection 130

20^a is not beveled and co-operates with both members 19^a, 19^b. These have their under surfaces inclined as shown in Fig. 24, and in this construction the under surfaces of 5 19^a, 19^b, are oppositely inclined. Hence when turned to the left from off position, the part 20^a engages a surface which deflects the flipper so as to give a quick make, but when turned back in the opposite direction 10 toward the off position, the flipper is not deflected since the part 20^a engages an inclined surface and the member 19^a is raised from its path. The action is similar with reference to the member 19^b. The overload and 15 no-voltage protective devices are interlocked mechanically with the reversing and controlling arm 75, so that the protective devices can be closed for starting up, only when the controlling arm 75 is in off position 20 and thus insures starting up under proper conditions with a protective amount of resistance in the circuit. The interlocking means in this case is shown as a pivoted arm 74^a having one end engaging a notch in the 25 hub of the no-voltage arm 73. Pivotedly connected to the arm 74^a is a rod 74^b, which is in turn connected to the pivoted lever 74^c. This lever has one arm 74^d extending into the path of the end of the controlling arm 30 75. A spring 74^e tends to keep the parts 74^b and 74^c in alignment and so tends to force the end of lever 74^c into the notch of the hub of arm 73 and also tends to force the arm 74^d into the path of the end of arm 75. 35 When in off position, the controlling arm 75 will raise the part 74^a and cause the end of lever 74^c to be withdrawn from its notch. Under these conditions, the protective devices may be closed, after which the circuit 40 will be completed by movement of the controlling arm 75. Hence, in starting up, the arm 75 must first be returned to off position.

If we assume that the controlling arm is turned to the right so as to engage the first 45 contact 76, current will pass from one supply line through the no-voltage and overload switches, overload coil 26 to conducting part 76^a, to strip 76^b, through the armature A to 50 76^c, in the controlling arm through 75^a, to the first contact 76, through the armature resistance to strip 76^d, through the overload switch blade 24^a to the other supply line. The motor at this time necessarily has its full 55 field strength, current passing from one side of the line through the field winding F to the strip 77^b, into the controlling arm through conducting portion 75^b, to strip 77^a, to strip 76^e to the other side of the line. When the arm is moved to cut out the armature resistance, the speed of the motor will 60 gradually increase. When all armature resistance is cut out, the conducting portion 75^b begins to pass over the contacts 77 and gradually inserts resistance in the field circuit. The weakening of the field in this

manner gives further increase of motor speed. When turning the arm to reverse, all the field resistance must be cut out and the armature resistance cut in. The armature circuit is then broken and protection of the 70 main contacts secured by means of the auxiliary contacts with a quick break in a magnetic field. The field circuit is not now broken or changed. When the controlling arm is turned to engage the resistance contacts 76^c, the circuits are similar except that the direction of current through the armature A is reversed giving a reversed rotation 75 of the motor.

Sometimes I use a reversing field rheostat 80 to secure reversal of the motor. In such cases I prefer to mechanically interlock or electrically functionally relate the starter and reversing field rheostat so that the reversing field rheostat must be in a condition corresponding to proper field strength of the motor when the starter arm is moved to close the circuit and start the motor. I also prefer to arrange the reversing field rheostat so that prior to reversing the field connections, 90 the movement of the reversing field controlling arm will cause the main circuit of the motor to be opened, for example by releasing the controlling arm of the starting device. After reversing the field connections the construction is such in my preferred form that the circuit can be again closed only when the field is of proper strength.

Fig. 26 illustrates one such construction 100 in which the interlocking means is mechanical and in Fig. 27 the parts are electrically interlocked so that the motor cannot be started under a weakened field.

Referring to Fig. 26, the controlling and 105 protective devices are similar to those described with reference to Fig. 1. The controlling arm of the reversing field rheostat consists of two conducting parts 78, 78' which pass over the field resistance contacts 110 78^a, 78^b and the conducting strips 78^c, 78^d. The shaft of the field rheostat carries a cam 79 having two depressed portions 79^a, 79^b for the rod 80 to drop into when the rheostat arm engages either the initial contact 115 78^a or initial contact 78^b, or contacts adjacent thereto, as may be desired. The rod 80 carries a yieldable section 80^a which projects in the path of the extension 80^b on the starting arm 5. This extension 80^b is so shaped that 120 the arm 5 is free to move to the off position, forcing the yieldable part 80^a out of its path, but when in off position can only be moved to close the circuit when the rod or part 80^a is out of the path of extension 80^b. The 125 portion 78 of the field rheostat arm is extended so that before the field circuit is broken, the extension will act to raise the pivoted lever 81 and open the circuit of the no-voltage magnet 21 at 81^a.

Assuming that the arm 5 is in off position, the overload switch will first be closed and unless the field rheostat arm engages either one or the other of the initial field resistance contacts, the starting arm cannot be moved to close the circuit. Hence the field rheostat arm must be turned to engage one or the other of the initial contacts, or contacts immediately adjacent thereto, giving the field of the motor its full strength, or in some cases nearly the full strength. The arm 5 may then be moved to close the circuit and cut out the armature resistance. The depressions 79^a, 79^b are preferably located as shown so that when the rod 80 enters them, the extended part of 78 will not raise the lever 81 to open the circuit of the no-voltage magnet and the initial contacts 78^a, 78^b should be long enough to accomplish the result desired, that is, allow the no-voltage circuit to be closed when starting. The no-voltage magnet 21 is connected across the line through the resistance 36 and switch 81^a. If we assume that the field rheostat arm engages the initial contact 78^a, the field circuit will extend from one side of the line within the overload switch to the initial contact 78^a, to conducting part 78, 78^c, through the field F, to 78^a, 78^b, to the other side of the line. Turning the rheostat lever to the right will now insert resistance in the field circuit and increase the speed of the motor. If it is desired to stop or reverse the motor, the field rheostat may be turned so as to cut out the field resistance and while still in engagement with the initial contact 78^a, the extension from the rheostat arm will raise the lever 81 and open the no-voltage circuit at 81^a. This will release the controlling arm 5 which will quickly move to off position and open the circuit at a point where protective means for minimizing the spark at auxiliary contacts is employed. This will leave the field and armature in a closed circuit and the continued turning of the field rheostat arm to open the field circuit will cause no appreciable sparking as the connection to the supply circuit is already broken. Hence the field rheostat contacts are protected from sparking in stopping or in reversing. For obtaining a reverse rotation of the motor, the field rheostat arm will be turned to the left to engage the initial contact 78^b and allow the rod 80 to drop into the depression 79^a. The motor may then be started by means of the controlling arm 5 and the field strength weakened if desired for further increasing the speed after the armature resistance is cut out.

The construction indicated in Fig. 27, is similar to that described with reference to Fig. 26 except that the mechanical means interlocking the field rheostat and starting arm is replaced by electrical means. In the present construction the field resistance re-

mains short circuited until the motor has been started and attained a predetermined speed or electromotive force at its terminals. The short circuit of the field resistance is from the initial resistance steps or wire connected thereto, through the solenoid switch 82, to conducting portion 82^a, with which the conductor 78 of the rheostat lever is always in contact. The position of the field rheostat arm will therefore have no effect unless the switch is open. The opening of this switch is controlled by the coil 82^b which is connected across the armature terminals of the motor and will act to open the switch only when the potential difference across the armature terminals is a predetermined amount. Hence with this construction the motor is always started under full field strength and its field cannot be varied until the motor has obtained a predetermined speed or until the electromotive force at the armature terminals attains a certain value and opens the short circuiting switch 82. The full resistance may then be varied as desired. The operation in stopping or reversing the motor by means of the field rheostat arm is similar to that explained with reference to Fig. 26.

In some cases, the use of a single magnetic blow-out in co-operation with a pair of auxiliary contacts may be insufficient to fully protect the parts or may require an undesirably large construction of the auxiliary contacts and blow-out for efficient service. I overcome this difficulty by the use of a plurality of auxiliary contacts, each having the break occur in the presence of a strong magnetic field and by having the auxiliary contacts connected in series with each other. The subdivision of the arc in this manner combined with the quick break in the presence of a strong magnetic field gives a very effective action even for the most exacting conditions.

Figs. 28 and 29 show a construction in which three auxiliary contacts are used in conjunction with the breaking of the circuit at a pair of main contacts of the circuit breaker. A portion of the circuit breaker arm is indicated at 83 which carries current to or from the main contact 83^a, making contact therewith in any suitable manner. The arm is shown as carrying an extension which supports a flipper 15 having the screws 16 for guiding and holding it and the spring 18 for pressing it outward as already explained. Insulated from the arm is an additional support 83^b, shown U-shaped, and each arm thereof carrying a spring pressed flipper 15. A flexible wire is shown connecting the arm 83 to the lower flipper 15 to insure good electrical contact and a flexible cable also connects the two upper flippers for the same reason. Fixed to the base or panel is a support 83^c carrying three U-shaped magnets 130

83^a, each having an auxiliary copper contact 13 fixed to its poles. The flippers 15 co-operate with the contacts 13 to break the circuit after the main contact is broken as above explained, and in the presence of a strong magnetic field between the poles of the U-shaped magnets. The auxiliary path of the current is from the arm 83 to the lower flipper 15, to lower auxiliary fixed contact 13, thence through the winding of the lower magnet 83^a, then through the winding of the central magnet 83^a, to the central auxiliary contact 13, to the central flipper 15, then to the upper flipper 15, to the upper auxiliary contact 13, through the winding of the upper magnet 83^a to the main fixed contact 83^a. It is thus seen that there are three pairs of auxiliary contacts connected in series which are adapted to break the circuit simultaneously. This form of contact may be applied to any of the previously described forms in which a single quick break auxiliary contact is used.

The various modifications above described are adapted for starting and controlling devices of moderate or usual capacity. The construction shown in Fig. 30 is adapted for very large capacity and by reason of being composed of a number of units may be built up to almost any capacity desired without the necessity of making new designs and patterns of parts which would be infrequently used. Moreover it is sometimes desirable, in order to avoid disturbance of the system, that the current taken from the supply mains suddenly, or at one instant, must not exceed a certain amount. This result may be attained in starting very large motors, by taking the large current needed in sections. For example, if a starting current of 2400 amperes is required, this, when taken at one time might be very objectionable and yet when taken in successive increments of 600 amperes would be satisfactory. By means of the present construction I attain this result. I also attain other important advantages which will be understood from the description.

Referring to Fig. 30 the main panel is indicated at 1 and although complete in itself, I show additional panels 1^a, 1^b, 1^c, in the present instance. The panels are shown in the same plane for convenience of illustration, but in reality are placed one behind the other. On the main panel is indicated the double pole circuit breaker having independently movable switch arms 51, the overload coil 52 and the latches 53, both of which are adapted to be tripped to release the spring pressed arms 51 by means of the plunger of the solenoid. I have shown the switch arms each provided with a plurality of quick break auxiliary contacts in series with each other having means for producing a strong magnetic field at each auxiliary contact, and the construction is substantially as shown in

Figs. 28 and 29. The lower fixed contacts with which the switch blades co-operate are provided with one or more extended clips so that contact is broken at the quick break auxiliary contacts for interrupting the circuit before it is broken at the lower contacts of the switch blades.

In order to prevent the closing of either pole of the double pole circuit breaker at a time when such closing would be undesirable, as might be the case when a protective amount of resistance is not included in the motor circuit at the time of starting, I provide interlocking means. In the present instance this is shown as a solenoid 84 having a core adapted to fall by gravity into the path of a projection 84^a extending from the movable arm of the circuit breaker. Each arm is provided with such a projection and each has its own solenoid. The construction is shown more clearly in Fig. 31. The solenoid 84 is supported some distance from the face of the panel and the circuit breaker arm cannot be closed unless the core of the solenoid is raised. The projection 84^a has a surface inclined in such a direction that when the circuit breaker opens, the plunger of the solenoid will be forced out of its path and the opening of the circuit breaker, therefore, is not interfered with. The coils of the solenoids 84 are connected in series across the supply mains through a switch 84^b, which has a spring adapted to hold the switch in open position. This switch is closed by the controlling resistance arm 5^a when the latter is in off position. As the closing of switch 84^b will cause the plungers of the solenoids 84 to be raised, the circuit breaker can be closed only when the starting arm is in off position. A protective resistance will, therefore, always be included in the motor circuit at the time of closing the circuit breaker, or the motor circuit will be opened at the resistance arm.

The resistance arm 5^a on the main panel is provided with auxiliary quick make and quick break contacts and magnetic blow out. The arm is shown as retained in its final position by the latch 85 in place of a no-voltage retaining magnet. This is to overcome the objection to such a magnet, which, if made very powerful in units of large capacity, might have considerable residual magnetism interfering with its reliable release and the watts required by the magnet may be quite considerable. The latch is released by the no-voltage device which consists of a solenoid 85^a having a plunger adapted to fall and trip the latch upon failure of current through the solenoid. The solenoid coil is connected across the line in series with a resistance 36 and in a circuit independent of the motor field winding. Means for automatically lifting the plunger of the solenoid to its operative position may

be provided either in the form of a mechanical lifter controlled by the resistance arm, or electrically. In the present instance I have shown electrical means whereby a heavy current is passed through the solenoid coil to raise the plunger, after which the current is reduced to an amount only sufficient to maintain the plunger in its raised position. The contact 85^b is in the path of the flipper 15 on the resistance arm, and when the resistance arm is moved in starting up the motor the engagement of the flipper 15 with contact 85^b will cause the resistance 36 to be shunted by the connection from contact 85^b to the solenoid coil, and a comparatively large current will pass through the same. After the plunger is thus raised, the contact at 85^b will be broken and the solenoid coil will then receive only its normal current.

I provide a laminated short circuiting contact 86 which is moved into short circuiting position through the movement of the resistance controlling arm, either directly by mechanical engagement as shown, or electrically by a coil which is energized or de-energized to cause the movement of the short circuiting switch when the resistance controlling arm reaches its final position. This short circuiting switch relieves the resistance controlling arm, or contacts thereof, from carrying any appreciable current, and the further advantage is attained that owing to the yieldability of the laminated switch, the resistance will be forced by this switch, in addition to the spring pressure, to start the arm when released by the latch 85.

For reversing the direction of rotation of the motor, I have shown a reversing switch 87 in the armature circuit. This reversing switch is interlocked so that it cannot be thrown when the armature is under running condition. This is accomplished by a solenoid 87^a having a core and a projection 87^b thereon which is raised in the path of the reversing switch and prevents its reversal when current passes through the solenoid coil. This coil is connected across the terminals of the motor armature. Hence to reverse the motor, it must first be stopped or the electro-motive force at its terminals decreased to a predetermined minimum. Reversing at an improper time is therefore avoided.

A field resistance controlling arm 88 is shown, and means is provided for functionally relating the parts so that the motor cannot be started when the field is weak. This is accomplished by a switch 88^a which short circuits the field resistance which may happen to be in circuit at the time of starting the motor. This switch is closed by a spring and may be retained in an open position by forcing the opposite end of the pivoted switch against the winding magnet 88^b. This magnet is in circuit across the

line with the no-voltage solenoid 85^a. When the magnet 88^b is deenergized, as when the motor is stopped, the switch 88^a will be closed and the field resistance short circuit-
ed. In starting the motor, the current 70 through the magnet 88^b is not sufficient to attract the armature 88^c on the switch lever, and the switch 88^a remains closed at the time of starting and is opened only by re-
turning the arm 88 to such a position that 75 all the field resistance is cut out. The ex-
tension of arm 88 then forces the armature 88^c against the retaining magnet and the field rheostat arm may then be moved to increase the field resistance as desired. 80 Starting up under a condition of weakened field is therefore avoided.

Referring now to the construction where-
by I provide means for taking the starting current from the line in successive incre-
ments, and whereby large resistance control-
ling capacity is attained by the addition of
units of similar character, I fix upon the
operating shaft 89 all of the resistance con-
trolling arms 5^a, 5^b, 5^c, and 5^d. These arms 90
are therefore all moved uniformly and si-
multaneously and coöperate respectively
with resistance contacts 4 on the main panel
and additional panels 1^a, 1^b, 1^c, respectively.
The no-voltage release for the resistance 95
arm 5^a, and the short circuiting switch 86,
suffice for the additional arms as well, but
each of the arms 5^b, 5^c, 5^d are provided with
auxiliary quick make and quick break de-
vices of the character already described. 100
The resistances controlled by the four arms
are connected in parallel when starting up
the motor, and therefore, are capable of car-
rying jointly a very large starting current.
Instead of placing all the resistances in par-
allel at one time when starting, I first con-
nect one of the four resistances in circuit,
then a second one in parallel therewith, then
a third in parallel with the first two, and
finally a fourth in parallel with the other 110
three. In this manner, the total current for
starting is taken, in successively increasing
sections, and less disturbance of the distrib-
uting system takes place. Also the total
current taken may be less than would be 115
taken in case the resistances were all placed
in circuit at one time, since the motor, if
lightly loaded, might start after the first or
second set of resistances are connected in
circuit, and in such case the entire starting
current will not be required. To accom-
plish this result, when the starting arm 5^a
is turned to close the circuit, its flipper will
make contact with the auxiliary contact 13
and connect one rheostat in circuit with the
motor armature, and a comparatively small
current is then drawn from the line and this
is readily carried by the auxiliary contact.
After the contact shoes of the arm 5^a have
engaged the initial contact 4^b, the flipper on 130

the arm 5^e will then engage its auxiliary contact and connect the second set of resistances in parallel with the first which will practically double the current taken from the line. After the contact shoes on the arm 5^e have engaged the initial contact 4^e, the flipper on the arm 5^f will engage its auxiliary contact and connect the three sets of resistances in parallel with the first two. After the contact shoes on the arm 5^f have engaged the contact 4^d, the flipper on arm 5^g will engage its auxiliary contact, and the fourth set of resistances will thus be connected in parallel with the other three. It will be noted that this result is obtained by locating the auxiliary fixed contacts and initial resistance contacts in proper relation to each other and by proportioning the initial resistance contacts so that contact is maintained by the preceding arms until all the resistance sets have been connected in parallel. Further movement of the controlling arm 5^a and its shaft 89 will gradually cut out sections of the different sets of resistances and bring the motor up to speed. When the arm 5^a is released all of the resistance arms will be returned to the off position simultaneously, and upon starting the action will be similar to that above described. Although I have shown four sets of resistances adapted to be connected in parallel it will be understood that any desired number may be used.

Although I have described various modified forms of construction it will be understood that my invention is not restricted to the various forms described, and that I am limited only as indicated by the following claims.

40. Instead of mounting the quickly movable auxiliary contact on the movable element and the coöperating contact, or magnetic blow-out, in a fixed position, these parts may be reversed in position in some cases.

45. Having thus described my invention, I declare that what I claim as new and desire to secure by Letters Patent, is,—

1. The combination of a source of electro-motive force, a translating device, a switch 50 for completing the circuit, said switch comprising an auxiliary independently movable contact carried by the movable element of said switch, and means for causing the quick closing of the circuit independently of the rate of movement of said switch.

2. The combination of main contacts, an independently movable auxiliary contact device, means for producing a magnetic field in the presence of the auxiliary contact device, and means for causing the auxiliary contact device to be quickly moved to make and break the circuit independently of the rate of movement of the main contact or contacts.

65. 3. The combination with a motor having a

shunt field winding, of a movable resistance controlling switch adapted to make and break the supply current to both the armature and field windings of the motor, an independently movable auxiliary contact device, one of the contact elements of said device being carried by said switch, means for causing said contact device to quickly break the circuit independently of the rate of movement of said switch, and means for producing a magnetic field in the presence of the auxiliary contact device. 75

4. The combination of a movable resistance controlling switch, an independently movable auxiliary contact device carried by 80 said switch, and means for causing said contact device to quickly close the circuit independently of the rate of movement of said switch.

5. The combination of a movable resistance controlling switch, an independently movable auxiliary contact device, one of the contact elements of said device being carried by said switch, means for causing said contact device to quickly close and break the circuit independently of the rate of movement of said switch, and means for producing a magnetic field in the presence of the auxiliary contact device. 85

6. The combination of a movable resistance controlling switch, an independently movable auxiliary contact device carried by said switch, and means for causing said contact device to quickly close the circuit and quickly open the circuit independently of 100 the rate of movement of said switch.

7. The combination of a movable resistance controlling switch, an independently movable auxiliary contact device carried by 105 said switch, means for causing said contact device to quickly close the circuit and quickly open the circuit independently of the rate of movement of said switch, and means for producing a magnetic field in the presence of said auxiliary contact device. 110

8. The combination with a motor having a shunt field winding, of a resistance controlling switch adapted to make and break the supply current to both the armature and field windings of the motor, an auxiliary 115 quick-acting contact device, part of said device being carried by said switch, and means for producing a magnetic field in the presence of said auxiliary device.

9. The combination of a stationary principal contact part, a coöperating movable principal contact part, a stationary auxiliary contact part, a coöperating movable auxiliary contact part carried by said movable principal contact part, and means for causing the auxiliary contacts to quickly close and complete the circuit and establish the flow of current independently of the rate of movement of said movable principal contact part. 120

10. The combination of a supply circuit, a translating device, an automatic switch for opening said circuit upon the occurrence of abnormal conditions, an auxiliary quick 5 break device for said switch, and a magnetic blow-out for reducing the arc developed when the quick break devices act.

11. The combination of a supply circuit, a translating device, automatic switches in said 10 circuit for opening the circuit upon the occurrence of different abnormal conditions, auxiliary quick break devices for said switches, and a magnetic blow out for reducing the arc developed when the quick break devices act.

12. The combination of a supply circuit, a translating device, an automatic switch responsive to overload, an automatic switch responsive to no-voltage, auxiliary quick 20 break devices for said switches, and a magnetic blow out for reducing the arc developed when the quick break devices act.

13. The combination of a supply circuit, a translating device, an automatic switch for 25 opening the circuit upon the occurrence of overload, an automatic switch for opening the circuit upon the occurrence of no-voltage, one of said switches being provided with a quick make device, and both of said switches 30 having means for quickly breaking the circuit.

14. The combination of a supply circuit, a translating device, an automatic switch for opening the circuit upon the occurrence of 35 overload, an automatic switch for opening the circuit upon the occurrence of no-voltage, auxiliary quick break devices for said switches, a magnetic blow-out for reducing the arc developed when the quick break devices act, and one of said switches having means for obtaining a quick make.

15. The combination of a resistance controlling switch, means for affecting the circuit upon the occurrence of no-voltage, 45 means for affecting the circuit upon the occurrence of predetermined current, auxiliary quick-acting contacts for opening the circuit, and a magnetic blow out for extinguishing the arc developed when the circuit connections are changed.

16. The combination of a motor-controlling rheostatic device, a no-voltage device functionally related thereto, a device for protecting the motor against abnormal current conditions, and means for opening the circuit quickly at the initial resistance contact independently of the rate of movement of the resistance controlling arm.

17. The combination of a motor-controlling 60 rheostatic device, a no-voltage device functionally related thereto, a device for protecting the motor against abnormal current conditions, means for opening the circuit quickly at the initial resistance contact independently 65 of the rate of movement of the controlling

arm, and means for producing a magnetic field at the point of opening the circuit.

18. The combination of a spring actuated motor controlling rheostatic movable element, a no-voltage device functionally related thereto, a device for protecting the motor against abnormal current conditions, means for opening and closing the circuit quickly by means of the resistance controlling arm independently of its rate of movement, and means for producing a magnetic field at the point of opening the circuit.

19. The combination with a motor having a shunt field winding, of a hand operated resistance controlling switch adapted to open 80 and close the armature and shunt field supply circuit, means for protectively affecting the circuit upon the occurrence of no-voltage, means acting independently of said first named means for opening the circuit upon 85 the occurrence of predetermined current, and a magnetic blow-out for extinguishing the arc developed when the circuit is opened by the hand operated switch.

20. The combination of a stationary principal contact part, a coöperating movable principal contact part, a stationary auxiliary contact part, a coöperating movable auxiliary part carried by said movable principal contact part, means for causing the 95 auxiliary contacts to quickly close and quickly open independently of the rate of movement of said principal contact part, and means for producing a magnetic field in the presence of the auxiliary contact.

21. The combination of a motor controlling rheostat, a no-voltage device responsive to a current which is independent of the current through the motor armature or field windings, said no-voltage device being protectively 105 related to said rheostat, an independently movable switch automatically responsive to abnormal current through said motor armature, said switch and rheostat being protectively related, and means for reducing 110 the injurious effects due to the arc developed in making and breaking the circuit.

22. The combination of a motor controlling rheostat, a no-voltage device responsive to a current which is independent of the current 115 through the motor armature or field windings, said no-voltage device being protectively related to said rheostat, an independently movable switch automatically responsive to abnormal current through said 120 motor armature, said switch and rheostat being protectively related, and means for producing a magnetic field for reducing the injurious effects due to the arc developed in making and breaking the circuit.

23. The combination of resistance contacts, a controlling arm, an independently movable contact carried by said arm and adapted to successively engage said contacts, and a spring at each end of said movable contact tending 130

23. To force the same in engagement with said resistance contacts, said springs being one in advance of the other with reference to the direction of movement of said contact when moved by said arm.
24. The combination of resistance contacts, a controlling arm, an independently movable contact moved by said arm and adapted to successively engage said contacts, and springs tending to force said contact in engagement with said resistance contacts, said springs being arranged so as to enable the contact to be raised clear of an obstruction at the forward end relatively to the direction of motion without breaking the contact at the rear portion of the movable contact.
25. In a rheostat, the combination of a series of fixed rheostat contacts, a slideable contact readily movable in a forward or backward direction over said contacts, two springs for maintaining contact between the slideable contact and fixed contacts, one of said springs being in advance of the other for the purpose set forth.
26. In a rheostat, the combination of a series of fixed contacts, a plurality of slideable contacts readily movable in a forward and backward direction over said fixed contacts, two springs for each of said movable contacts for maintaining contact with the fixed contacts, one of said springs being in advance of the other for the purpose set forth.
27. The combination of a fixed contact, a movable contact, and means for moving said movable contact, said means comprising a plurality of universal joint pivotal connections with said movable contact.
28. In a rheostat, the combination of a plurality of fixed resistance contacts, a movable contact, and means for moving said movable contact, said means comprising a plurality of pins making a pivotal connection on their outer ends with said movable contact.
29. The combination of a fixed contact, a movable contact, and means for moving said movable contact, said means comprising a plurality of yieldable pins making a universal joint pivotal connection at their ends with said movable contact.
30. The combination of a fixed contact, a movable contact, and means for moving said movable contact, said means comprising a member having a plurality of recesses, a spring seated against the inner ends of each of said recesses, and an element forced by each of said springs to pivotally engage
31. The combination of a yieldable laminated fixed contact, a movable element, and a yieldable contact carried by said movable element, said yieldable contact being adapted to engage said first named fixed contact.
32. The combination of a motor starting rheostat having a movable element for gradually cutting out the resistance in series with the armature of the motor, an auxiliary contact carried by said element for effecting a quick action in changing the circuit connection, and means engaged by said auxiliary contact when said element is in the resistance all out position for connecting the field winding of the motor across the supply circuit without including the starting resistance.
33. The combination of a controlling switch, means controlled by the movement thereof for quickly breaking the circuit at one point, means for producing a magnetic field where the current flow is finally interrupted, and a functionally related overload circuit breaker adapted to break the circuit at another point.
34. In a rheostat, a series of stationary contact parts, a movable element coöperating therewith and adapted when moved to vary the resistance in circuit, said element comprising a plurality of independently self-adjusting skate-like contacts, each contact being spring pressed at two points one of which is in advance of the other considered relatively to the direction of motion of said contacts.
35. In a rheostat, a series of stationary contacts, a movable element having a plurality of skate-like movable contact parts arranged side by side and adapted when moved to coöperate with said stationary contacts, and means for forcing said movable contact parts independently into self adjusting contact.
36. In a rheostat, a plurality of independently self adjusting contact skates, and a series of stationary rheostat contacts engaged by said skates, the material of said skates and stationary contacts being different.

In testimony whereof I affix my signature, in presence of two witnesses.

H. WARD LEONARD.
